UNITED STATES PATENT OFFICE.

CARRIE EASTON, OF SAN FRANCISCO, CALIFORNIA.

HAT-HANGER.

SPECIFICATION forming part of Letters Patent No. 629,154, dated July 18, 1899.

Application filed February 1, 1899. Serial No. 704,158. (No model.)

To all whom it may concern:

Be it known that I, CARRIE EASTON, a citizen of the United States, residing at San Francisco, in the county of San Francisco and State of California, have invented certain new and useful Improvements in Hat-Hangers; and I do hereby declare the following to be a full, clear, and exact description of said invention, such as will enable others skilled in the art to which it most nearly appertains to make, use, and practice the same.

This invention relates to devices for suspending articles of clothing or the like, and more particularly to a device which provides means for hanging the hat or other light articles in theaters and places of amusement where these articles are a source of annoyance after removal; and it consists in the novel arrangement and construction of the parts hereinafter more fully set forth.

In the drawings, Figure 1 is a side elevation of a device constructed in accordance with this invention. Fig. 2 is a rear elevation of the same.

The device is preferably constructed of wire of small gage and springy temper. The sections of rubber tubing A' A² are placed over the portions of the loop A which come in contact with the piece of furniture, such as the backs of opera-chairs, to prevent marring of the same, the portion A' being strung onto the wire and confined in the bend of the same, where it turns upon itself to form the curvature of the loop A. One of the free ends of the wire after the loop has been completed is given a turn around the other extension of the loop at A³, the portion A⁴ being extended therefrom and the end bent to form the keeper A⁵ for the sharpened end A⁶ of the hook A⁷.

Just below the winding A⁸ the turn A⁸ is formed, into which the spring-clamp B is hung. This spring-clamp consists of a single piece of wire bent to form the spiral ring B', engaging the smaller hanger A⁸. Extending from the portion B', crossed upon themselves, are the extensions B² B³, ending in the flattened spiralities B⁴ B⁵, which are separated

against the tension of the spiral B' to insert the article to be suspended between the spirals B⁴ B⁵, where it is held till released in the proper manner.

In utilizing the device as thus described—taking, for example, its use in the theater—the loop A is sprung over the back of the chair in front, which it engages snugly by reason of its springy nature. The portion from the rubber tubing A' upward to the top of the loop is made perfectly straight, so as to lie as nearly flush as possible with the chair-back to avoid interference with the back of the occupant of the same. When the device is thus in position, the hooks and clamps or the like attached to the loop A may be made use of to hold the hat or any other object for which they are suitable, avoiding the annoyance of holding these articles in the lap.

If it is desired to attach the device to an upholstered surface or portière, the device may be inverted, the hook A⁷ engaging the fabric and serving the purpose of the loop A.

While the form as shown in the drawings is preferred, it is obvious that various changes therein may be made without altering the spirit of this invention, such as increasing or decreasing the number of hooks, clamps, or other suspending means attached to the loop A. Further, while wire is the preferred material of construction sheet metal may be struck into forms approximately similar to those shown as constructed of wire.

It is the intention to manufacture these devices of a size that may conveniently be carried in the pocket or purse. It is also intended to provide each device with a suitable case or receptacle, such as cases for spectacles.

Having thus described this invention, it is claimed—

As a new article of manufacture, a hanger for articles of apparel, or the like; consisting of spring-wire doubled and bent backward upon itself to form a suspending-loop; one extension of the wire forming the said suspending-loop, being bent into the form of a

hook and being also bent to produce an eye in the shank of said hook; the other extension of the wire forming the suspending-loop being coiled around the shank of said hook; adjacent to the suspending-loop; the end of said extension being bent to act as a keeper for the sharpened end of said hook; a clamp suspended from said suspending-loop by en-

gaging the eye formed in the shank of said hook, substantially as described. 10

In testimony whereof I have hereunto set my hand this 17th day of January, 1899.

CARRIE EASTON.
